FULLING MACHINE OF THE ROLLER TYPE

Marcel Cassé, Essonnes, France

Application January 15, 1937, Serial No. 120,803
In Belgium December 16, 1936

9 Claims. (Cl. 28—6)

The machines which are most commonly employed for the fulling of textile goods consisting of hair or woolen felt particularly the hat-blanks used in the hat-trade, consist essentially of rollers which are placed close together and are arranged in two opposite sets, between which the said hat-blanks are passed. Each of the said rollers is set in continuous rotation about its longitudinal axis, and by this movement, the said 5 hat-blanks are drawn forward. On the other hand, one or both of the two rollers of each set of two co-operating rollers is given a rectilinear, reciprocating displacement of small amplitude, parallel to its axis. This reciprocating movement is termed "vibration", and produces the fulling. The hat-blank, or like article, is pressed 10 between two opposite co-operating rollers, and is subjected, on each of its faces, to the alternate action of the said rollers. These movements, together with moisture, heat and pressure, cause 15 the intermingling and the intimate contact of the fibres which is termed the fulling.

Such machines operate at a slow rate, and several hours are required for the complete fulling 20 of a hat-blank or like article. Increase of their production cannot be obtained by increasing the amplitude of the vibration, for if this amplitude should exceed a few millimetres, the surface of the rollers wears the surface of the hat-blanks, 25 and the fibres of the felt will separate instead of being fulled.

Trials have been made to increase the frequency of the vibration by particular mechanical arrangements, and the machine which will 30 be hereinafter described is an example of such an arrangement, but no change has been hitherto made in the principle of operation of the above-mentioned machine.

An improvement in the production has also 35 been sought for by an alternate variation of the pressure of the rollers upon the hat-blanks, thus producing a "fullering" effect. This alternate pressure is at the maximum at the time of the maximum speed of the vibration.

It is none the less true that the principal effect 40 of the fulling is obtained by the movement of vibration. During each vibration, the relative speed of the two opposite rollers, which has at first a zero value, then passes through a maximum, comes again to zero, and then passes 45 through a maximum in the contrary direction, then coming to zero. In each axial vibration, we thus have two inoperative periods at which the speed has a zero value. At this time, there

will be no relative displacement of the rollers, and no fulling action will take place.

On the other hand, it is a known fact that the automatic "increasing" offers a great advantage in a fulling machine during the fulling operation. This increasing consists in the relative displacement of the two faces of the hat-blank or like article which is flattened between the rollers in such a way that the crease or creases formed by the flattening of the article will change 10 their position upon said article, and thus the latter may remain for a longer time in the machine, without any excessive risk that the mark of the crease or creases shall be permanent.

In particular, in the case of hat-blanks for 15 the hat-trade, the problem of the increasing cannot be perfectly solved, owing to the fact that the hat-blanks have a conical shape, and that during the increasing operation it should be necessary to displace both faces of each blank by 20 amounts increasing from the top to the edge or base of the blank.

In the machines exclusively provided with cylindrical rollers, four principal methods have 25 been hitherto employed for this purpose.

(a) A permanent difference in the speed of the lower and the upper rollers is provided; each of these sets of rollers engages with one face of the blank to be fulled, and the difference in speed causes the relative slipping of the two 30 faces.

(b) The rollers, which all rotate at the same speed, have different diameters; this arrangement provides for a progressive variation of the relative speeds of the rollers, but it complicates the 35 construction of the machine and the replacement of the rollers.

(c) The rollers have on their surfaces one or more screw-threads, which are inclined in the same direction for each set of rollers; as the 40 rollers of the adjacent sets rotate in the contrary direction, the screw-threads have a tendency to displace each face of the blank in the axial direction.

(d) One of the sets of rollers is entirely displaced, in a direction parallel to the axes of the rollers, by a slow movement of translation which is parallel to their axes, and is necessarily alternating; this arrangement will thus produce the same effect as the above-mentioned screw-threads. It has an advantage from the fact that it can be eliminated at certain times in the fulling operation.

The methods *a* and *b* provide for a longitudinal 55

uncreasing, i. e., perpendicular to the axes of the rollers.

The methods *c* and *d* provide for a transverse uncreasing.

5 The present invention has for its object to provide an improved fulling machine, in which due account is taken of the preceding considerations.

According to one feature of the invention, means are provided for imparting to at least one 10 of the rollers of each set, an alternate oscillation about its longitudinal axis, this oscillation constituting a circumferential vibration having the same frequency, or a frequency which is a multiple or a submultiple of the frequency of 15 the axial vibration of the said roller or of its co-operating roller, and being preferably such that the maximum relative speed of this second movement shall take place at the time when the axial vibration is inoperative.

20 Thus the phases of the two vibrations are alternate, and are displaced by a quarter of a period.

The inoperative times of the axial fulling are thus occupied by the circumferential fulling, and inversely. Hence, the fulling becomes continuous, thus at least doubling the production of the 25 machine, while improving the quality of the felt, which is now more homogeneous.

An alternate variation of pressure may be combined with the aforesaid movements, but its frequency need not have any relation to the frequency of the vibrations.

According to another characteristic, in view of the uncreasing, the machine comprises a device adapted to produce, at will, a difference in the 30 speed of the upper and lower rollers, and the action of this device can be readily eliminated or again established at any time.

This device allows the fuller to employ the uncreasing device when he feeds the hat-blanks, 40 or other articles, in a certain position, and to eliminate it if he should feed the blanks with the top part in front, for instance, and thus he will avoid all distortion of the said blanks.

In the accompanying drawings, which are 45 given solely by way of example:

Fig. 1 is a diagrammatic vertical section, perpendicular to the rollers, of a simple form of machine improved in accordance with the invention.

Fig. 2 is a section of a mechanism for driving 50 the upper rollers, this mechanism being shown in vertical section on its longitudinal axis, that is, transversely to the rollers.

Fig. 3 is a partial section on the line 3-3 of Fig. 2.

55 Fig. 4 is a vertical section on the line 4-4 of Fig. 5, that is, on the axis of one of the lower rollers, relating to a more complete construction of a machine according to the invention; (in this figure, one of the upper rollers is also shown in 60 section, although in fact, the upper rollers are laterally displaced with reference to the lower rollers).

Fig. 5 is a corresponding plan view.

Fig. 6 is a vertical section on the line 6-6 of 65 Fig. 5.

Figs. 7 and 8 are enlarged partial views corresponding respectively to the left-hand part of Fig. 4, i. e. to the mechanism for producing the axial vibrations, and to the upper right-hand corner of Fig. 5, i. e. to the device for operating the uncreasing.

Fig. 9 is an elevational view of the machine.

Fig. 10 is a vertical section of the device for ensuring the water circulation in the machine.

75 In the embodiment shown in Figs. 1 to 3, the

machine comprises a main frame 1 provided with two lateral cheeks 2, in which are journalled a certain number, four for instance, of lower rollers 3 which are rotated by any suitable means (not shown) in the direction of the arrow *f*¹.

Between the said rollers, and above the same, are mounted the upper rollers 4, each of which is journalled at either end in a casing 5. Each casing consists of two half-shells, connected together by bolts 6, and is slidable, by means of 10 sleeves 7 (Fig. 3), upon two bars 8 which are parallel to the axes of the rollers 4 and are supported by the cheeks 2. In the interior of one of the casings 5, the rollers 4 carry worm-wheels 9 (Fig. 2) in engagement with worms 10 which 15 are cut upon a shaft 11. This shaft 11 is rotatable and slidable in bearings 12 (Fig. 2) forming part of the casing 5. The said shaft 11 has an oblique journal 13 upon which a member 14 is rotatable, said member being pivoted by a ball-and-socket joint in the end of a link 16 which is pivotally mounted at 17 on the casing 5. At each end of the shaft 11 is an eccentric journal 18. These eccentric journals are rotatable in two 20 respective bearings 19 each located at the end of a link 20 (Fig. 3), pivoted at the other end to the machine frame, on a transverse axle 21.

At one end, the shaft 11 carries a pulley 22 driven by a belt which rotates it in such direction that the upper rollers 4 will be driven in the direction of the arrow *f*² (Fig. 2).

The machine is completed by a table 23 (Fig. 1), heated or not; an endless band 24 travels above the said table, and it consists of woolen fabric, canvas, or rubber belting. The band 24 is engaged between the upper rollers 4 and the lower rollers 3, and is stretched between the last lower roller 3^a and an auxiliary roller 25, situated in front of the table 23.

A second endless band 26, mounted on rollers 27, travels in contact with the band 24 upon the last roller 3^a, and moves along with the lower part of this band 24, as far as the upper part of said band, tangent to the roller 25.

The operation is obvious. The shaft 11 which is driven by the pulley 22, imparts—through the worms 10 and the worm-wheels 9—a continuous movement of rotation to the rollers 4 in the direction of the arrow *f*². On the other hand, the eccentric journals 18 combined with the links 20 50 impart to the casing 5 an alternate movement parallel to the axis of the rollers 4. These latter will thus be given, by the casing 5, an axial vibration, i. e., an alternate movement of translation in the axial direction. Furthermore, under the action of the oblique journal 13 and of the members 14 and 16, the shaft 11 is given an alternate movement in the direction of the arrow *f*³, and in the contrary direction, at the same frequency as the preceding, and said shaft slides in the casing 5. The worms 10, which participate in this longitudinal movement of oscillation, operate upon the worm-wheel 9 after the manner of racks, thus imparting to said wheels a circumferential vibration having the same frequency as the axial vibration. The inclination of the said journal 13 is so arranged with reference to the eccentricity of the journals 18, that the maximum rate of axial vibration will be obtained at the time of the minimum rate of the radial 60 vibration.

The fuller places the hat-blanks to be fulled, upon the upper part of the band 24, which is engaged between the adjacent sets of rollers 3 and 4, thus drawing the said hat-blanks between 70 75

the rollers which are given the various movements above described. The auxiliary band 26 ensures the return of the said blanks into a position in front of the operator upon the table 24.

5 In order to provide for the uncreasing, the rate of rotation of the lower rollers 3 may be made different from that of the upper rollers 4, by means of a device similar to the one which will be further described.

10 Figs. 4 to 10 represent another machine in accordance with the invention, comprising, above the main frame 1, a set of lower rollers 3 and a set of upper rollers 4 which are set off transversely with reference to the lower rollers in 15 such way that their axes will be situated midway between the axes of two corresponding lower rollers.

15 All of the said rollers consist, for example, of a cylindrical surface portion which is held between two end-pieces 28 by tie-rods 29.

20 The said upper rollers 4 and lower rollers 3 are rotated in the direction of the arrows f^1 and f^2 respectively (Fig. 4). On the other hand, the lower rollers 3 are given vibratory movements in the 25 axial and also in the circumferential direction.

25 In order that the parts in alternating movement shall be as light as possible, and also that they shall be well balanced, so as to avoid jarring of the machine, each vibrating roller 3 is provided with separate driving means, the vibrations of any two consecutive rollers 3 having a phase displacement of 180° .

30 In a casing 5 secured to the main frame 1, is mounted a crank-shaft 30 (Figs. 4, 5 and 7) which carries as many eccentric journals as there 35 are lower rollers 3. The eccentricities of any two adjacent journals are displaced by 180° , according to the preceding considerations. Links 31 are 40 pivotally connected at one end upon the said journals, respectively. Each link carries at the other end a hemispherical cup 32 (Figs. 4 and 7). The said cup is held between two correspondingly curved members 33, 34, in which it is movable. The member 34 is mounted on the end of a rod 35 45 which is secured by a nut 36 to a sleeve 37 having a flanged end 38.

The member 33 and the flange 38 are held together by screw-studs 39.

50 The sleeve 37, which is rotatable and slidable in the bore of a sleeve 40 mounted in the casing 5 containing the mechanism, carries at its end situated at the exterior of the said casing a coupling disc 41. The said disc is assembled with a second disc 42 which is connected with one of 55 the roller 3.

The said roller carries at the other end a journal 43 (Fig. 4) which is rotatable and slidable in a bearing 44 mounted on the machine frame 1.

To the main crank-shaft 30 is keyed a worm-wheel 45 (Fig. 5) engaging a second worm-wheel 46 (Figs. 5 and 6) keyed to a vertical shaft 47.

60 The said vertical shaft comprises, on either side of the wheel 46, two eccentric journals 48 and 49 (Fig. 6) which are displaced by 180° . With 65 reference to the eccentricities of the main shaft 30, the eccentricities of the vertical shaft 47 are displaced by 90° . Upon the said eccentric journals 48-49 are mounted respective links 50-51 (Fig. 6), and said links—through the hemispherical members 52—are pivoted to discs 53 mounted upon two shafts 54-55 respectively (Figs. 4, 5, 7). The shafts 54-55 carry respectively a gear wheel 56-57 (Fig. 6). These two wheels 70 75 are in geared engagement and their teeth have

a sufficient length to allow them to slide while remaining in engagement.

Thus the shafts 54 and 55 are in constant rotation in contrary directions. Each shaft carries worms 10 in engagement, in pairs, with 5 worm-wheels 9 rotatably mounted on the sleeves 40 actuating the lower rollers 3. The worm-wheels 9 are connected as to rotation with said sleeves, and hence with the said rollers, by studs 39 which are inserted into the said wheels. Any 10 two consecutive wheels 9 are driven respectively by a worm located on the upper shaft 54, and by a worm located on the lower shaft 55. As the 15 said worms rotate in contrary directions, the result will be that all of the lower rollers 3 will 15 rotate in the same direction.

The upper shaft 54 extends outwardly of the casing 5, and it carries on its outer end two pulleys, or a pulley with two grooves 58-59 of different diameters, which are connected (Fig. 5) 20 by two belts 60, 61 to two pulleys 62-63 (Figs. 5 and 8) which are loose upon a socket 64 mounted on a shaft 65. The pulleys 62-63 carry respectively conical members 66 or 67, 25 adapted for engagement with two respective conical members 68, 69 secured to the shaft 65. For this purpose, a rod 70 slidable in a bore in the shaft 65, is connected with the socket 64 by a pin 71 extending through two apertures 72 pierced in the said shaft. On the end of the shaft 10 30 is mounted a stop 73, preferably upon ball bearings, which is acted upon in order to couple one or the other of the two pulleys 62, 63. This action is under the control of the fuller occupied with the machine, and is transmitted, for example, by a hand-wheel 74, a rod 75 and a lever 76 (Fig. 9).

The shaft 65 is rotated by the main crank-shaft 30, which carries one or more pulleys at one end; Fig. 5 shows two such pulleys 77, 78, 40 which drive corresponding pulleys 81-82 by belts 79, 80, respectively (Figs. 5 and 6), keyed to the shaft 65. By the use of either set of pulleys, different speeds can be obtained.

To the shaft 65 is keyed a long worm 83 (Figs. 45 4, 5, 9) in engagement with the worm-wheels 84, each of which is secured to a respective upper roller 4.

The diameters of the set of pulleys 58, 62 are such that the upper rollers 4 and the lower rollers 50 55 3 will rotate at the same speed, and the other set of pulleys 59, 63 is such that the upper rollers 4, for instance, will rotate at a slower speed than the lower rollers 3.

The shaft 83 is arranged below the rollers 4, 55 in such way as to be compatible with the vertical movements of the said rollers, to whatever degree.

The said rollers 4 are in fact journalled in 60 bearings 85 (Fig. 4) upon which are mounted the sleeves 86, slidable in two respective lower cross-pieces 87 (Figs. 4 and 9) which are movable, in translation, along two uprights 88 mounted on the main frame 1. Each sleeve 86 carries at the exterior a stop 89 (Fig. 4) slidable 65 in a longitudinal groove 90 in the cross-piece 87, thus limiting the upward movements relatively to the said cross-piece. The said cross-pieces carry two rods 91 (Fig. 9) which are slidable in an upper cross-piece 92, whose position in height 70 along the uprights 88 is adjustable as may be desired. The rods 91 are provided with nuts 93 or other stops, and thus the cross-piece 92, when it is raised, will also raise the lower cross-piece 87.

In the upper cross-piece 92 are screwed the rods 94 (Figs. 4 and 9), on the ends of which are mounted pistons 95, each of which is slideable in one of the sleeves 86 carrying the bearings 85 of the rollers 4. A spring 96 is located between the bearing 85 and the piston 95, in such way that when the rollers 4 bear upon the lower rollers 3 and when the cross-piece 92 is sufficiently lowered, the springs 96 will be compressed, and will thus press the rollers 4 upon the rollers 3. This pressure is adjustable, by the vertical adjustment of the upper cross-pieces 92.

The movements of the cross-pieces 92 along the uprights 88 may be provided for in the following manner. In these two cross-pieces 92 is journalled a driving shaft 97 (Figs. 4 and 9) upon the end of which is mounted a hand-wheel 98 or like operating device. The said shaft 97 carries, in the interior of each cross-piece, a worm 99 (Fig. 4) engaging a worm-wheel 100 which is rotatable together with a pinion 101 engaged with a rack 102 (Fig. 9) which is formed on the side of a corresponding upright 88 mounted on the main frame 1. A protecting sleeve 103, secured to the cross-piece 92, covers each rack 102.

As in the first embodiment, the machine comprises an endless band 24 (Figs. 5 and 9) which is mounted upon rollers 104 and 105 and serves to convey the hat-blanks or other articles to be fulled, to the first pair of rollers 3, 4. In the rear of the last pair of rollers 3, 4, is mounted a deflecting device 106 (Fig. 9) which ends at a point above a second endless band 107, stretched between two rollers 108, 109 which are driven from the shaft 83 through a set of gearing 110 (Figs. 4 and 9).

The machine is completed by a water circulation device. The vertical shaft 48 (Fig. 6) carries at the top a flywheel 111 adapted to regulate its movement, and also a pulley 112 which drives—through a horizontal belt and a second pulley 113 (Fig. 10)—a vertical shaft 114. The said shaft is journalled at its upper end in a casing 115 provided with ball bearings, and it hangs freely in a tube 116 the lower part of which is immersed in the receptacle 117 of the machine. To the lower end of said vertical shaft 114 is secured a propeller 118 or a wheel of a centrifugal pump. This forms a device for hot water circulation, in which no stuffing-boxes are employed.

The water which is elevated by the propeller 118 is delivered through a spout 119 into an upper receptacle 120 (Figs. 4 and 10) the bottom of which is perforated in coincidence with the rollers 4 above which it is situated. Thus the water is delivered upon said rollers, and it is taken up at a point below the rollers 3, by a basin 121 from which it is returned to the receptacle 117.

The operation of the said machine is as follows.

The shaft 30 is the driving shaft. It is driven by the main pulley 122 (Fig. 5). The said shaft imparts—through the links 31—the axial vibrations to the lower rollers 3.

On the other hand, the said shaft 30 drives—through the gearings 45 and 46—the vertical shaft which imparts, through the eccentrics 48 and 49, a longitudinal alternate movement to the shafts 54 and 55. The shaft 54 is driven by one of the sets 58, 60, 62 or 59, 61, 63, from the shaft 83, which latter is actuated by the shaft 30; the lower shaft 55 is driven by the gearings 56, 57.

The two worm shafts 54 and 55 thus have a movement of rotation and a movement of oscilla-

tion. The said shafts impart these movements to the wheels 8 and hence to the rollers, which are thus rotated and are subjected to a circumferential vibration which is superposed upon the movement of rotation.

It will be seen that the circumferential movements of the rollers 3 may be imparted by a single shaft 54 or 55. But the use of two shafts will permit, by displacing their alternating movements of 180° of compensating the reactions of inertia, and of preventing all jarring of the machine.

The travel of the hat-blanks to be fulled, is as follows. They are placed by the fuller upon the band 24, which feeds them between the first pairs of rollers. They then proceed between the succeeding rollers, being drawn forward by the said rollers.

When they are discharged from the last pair of rollers, the hat-blanks drop down. They are guided in this movement by a small deflecting device 106, and then come upon the horizontal band 107 which is stretched between the rollers 108 and 109, which bring them to the front, at which point the fuller can seize them and can send them again through the machine.

The uncreasing is obtained, at the proper times, by uncoupling—by the hand-wheel 74—one of the pulleys 62 or 63 and by coupling the other pulley.

Obviously, the invention is not limited to the embodiments herein described and represented, which are given solely by way of example. In the embodiments set forth, it is supposed that the two vibrations, axial and circumferential, are produced by the same rollers, but it is evident that such vibrations may be distributed between the two sets of rollers, or that each of these two sets may be subject to the two vibrations.

Having now described my invention what I claim as new and desire to secure by Letters Patent is:

1. A fulling machine comprising in combination two sets of parallel rollers, means for imparting to the rollers of one of said sets of rollers a uniform rotary movement in one direction and to the rollers of the other of said sets of rollers a uniform rotary movement in the contrary direction, said two sets of rollers being arranged one above the other in spaced relation so that the articles to be fulled which are passed between said two sets of rollers are suitably compressed, means adapted to impart to at least one of said two sets of rollers, an axial vibration i. e. a reciprocating longitudinal movement parallel to their axes and means adapted to impart to at least one of said sets of rollers a circumferential vibration i. e. an oscillation movement about their axes, said oscillatory movement being superposed to the uniform rotary movement.

2. A fulling machine comprising in combination two sets of parallel rollers, means for imparting to one of said sets of rollers a uniform rotary movement in one direction, worm wheels secured to the rollers of said other set of rollers, a worm engaging said worm-wheels, bearings in which said worm is adapted to rotate and slide, driving means adapted to rotate said worm so that said other set of rollers rotate in a direction contrary to the direction of movement of said one of said sets of rollers, means adapted to impart to said worm a reciprocating longitudinal movement and means adapted to impart to at least one of said sets of rollers an axial vibration.

3. A fulling machine comprising in combina- 75

tion two sets of parallel rollers, means for imparting to one of said sets of rollers a uniform rotary movement in one direction, worm wheels secured to the rollers of said other set of rollers, 5 a worm engaging said worm-wheels, bearings in which said worm is adapted to rotate and slide, driving means adapted to rotate said worm so that said other set of rollers rotate in a direction contrary to the direction of movement of said one 10 of said sets of rollers, an oblique journal on said worm, an oscillating bearing mounted on said oblique journal in fixed longitudinal relation with reference to said journal, a pivot the position of which is fixed with reference to said bearings, a 15 link pivotally connected on one end to said oscillating bearing and on the other end to said pivot, whereby a reciprocating longitudinal movement is imparted to said worm and means adapted to impart to at least one of said sets of rollers an 20 axial vibration.

4. A fulling machine comprising in combination two sets of parallel rollers, means for imparting to the rollers of one of said sets of rollers a uniform rotary movement in one direction and 25 to the rollers of the other of said sets of rollers a uniform rotary movement in the contrary direction, said two sets of rollers being arranged one above the other in spaced relation so that the articles to be fulled which are passed between 30 said two sets of rollers are suitably compressed, bearings adapted to rotatably support said two sets of rollers, means adapted to impart to at least one of the bearings of each roller of at least one set of rollers a reciprocating movement along 35 its axis, the other bearings of said one set of rollers being adapted to permit a sliding movement of the rollers, and means adapted to impart to at least one of said sets of rollers a circumferential vibration.

40 5. A fulling machine comprising in combination two sets of parallel rollers, means for imparting to the rollers of one of said sets of rollers a uniform rotary movement in one direction and to the rollers of the other of said sets of rollers a uniform rotary movement in the contrary direction, said two sets of rollers being arranged one 45 above the other in spaced relation so that the articles to be fulled which are passed between said two sets of rollers are suitably compressed, members in which are journalled said rollers, fixed 50 guides parallel to the axes of said rollers and on which said members are adapted to slide, means adapted to impart to said members a reciprocating movement on said fixed guides and means adapted to impart to at least one of said sets of rollers a circumferential vibration i. e. an oscillatory movement about their axes, said oscillatory movement being superposed to the uniform 55 rotary movement.

6. A fulling machine comprising in combination two sets of parallel rollers, means for imparting to the rollers of one of said sets of rollers a uniform rotary movement in one direction and to the rollers of the other of said sets of rollers a uniform rotary movement in the contrary direction, said two sets of rollers being arranged one above the other in spaced relation so that the articles to be fulled which are passed between said two sets of rollers are suitably compressed, fixed 10 bearings in which said rollers are adapted to rotate and slide, means adapted to impart to at least one of said sets of rollers a reciprocating longitudinal movement, and means adapted to impart to at least one of said sets of rollers a circumferential vibration, i. e. an oscillatory movement about their axes, said oscillatory movement being superposed to the uniform rotary movement.

7. A fulling machine as claimed in claim 6 in 20 which said means adapted to impart to at least one of said sets of rollers a reciprocating longitudinal movement comprise a rotary crank-shaft arranged transversely to the rollers, ball-and-25 socket joints on the ends of the rollers and links adapted to connect the crank pins of said crank shaft to said ball-and-socket joints.

8. A fulling machine as claimed in claim 2 in 30 which said means adapted to impart to said worm a reciprocating longitudinal movement comprise a crank shaft, a member mounted on the end of said worm and adapted to permit rotation of said worm while said member remains stationary and of transmitting to said worm longitudinal stresses, and a link connected at one end to a crank-pin of said crank shaft and on the other end to said member.

9. A fulling machine comprising in combination two sets of parallel rollers, means for imparting to one of said sets of rollers a uniform 40 rotary movement in one direction, worm wheels secured to the rollers of said other set of rollers, a first worm arranged above said other set of rollers and engaging a first group of alternate worm-wheels, a second worm arranged below said other set of rollers and engaging the other group of alternate worm wheels, bearings in which said worms are adapted to rotate and slide, driving means adapted to rotate said first worm in one 45 direction, a gearing adapted to connect said first worm with said second worm so that the latter rotates in the opposite direction to that in which rotates said first worm, the first and second worms being adapted to rotate the worm-wheels in the same direction, means adapted to impart to said worms a reciprocating longitudinal movement and means adapted to impart to at least one of said sets of rollers an axial vibration.

MARCEL CASSÉ.
